UNITED STATES PATENT OFFICE.

LOUIS IVES, OF DEARBORN, MICHIGAN.

AUTOMATIC DOOR OPENING OR CLOSING DEVICE.

SPECIFICATION forming part of Letters Patent No. 795,225, dated July 18, 1905.

Application filed May 23, 1903. Renewed June 22, 1905. Serial No. 266,506.

To all whom it may concern:

Be it known that I, LOUIS IVES, a citizen of the United States, residing at Dearborn, county of Wayne, State of Michigan, have invented a certain new and useful Improvement 5 in Automatic Door Opening or Closing Devices, of which the following is a specification, reference being had to the accompanying drawings, which form a part of this 10 specification.

My invention has for its object certain new and useful improvements in an automatic door opening and closing device, whereby a person by stepping upon a yielding platform 15 will cause the door to be automatically opened, the door automatically closing when the pressure upon the platform is relieved therefrom. Obviously such a device will be particularly important and valuable for a 20 great variety of uses—as, for example, in stores, houses, barns, and as applied also to gates; but I would have it understood that I contemplate its application to any use to which it may be applied.

25 To these ends my present invention consists of the construction, combination, and arrangement of appliances hereinafter described and claimed, and illustrated in the accompanying drawings, in which—

30 Figure 1 is a view in perspective, showing features of my invention. Fig. 2 is a vertical longitudinal section through the yielding platform, the platform being in its normally elevated position. Fig. 3 is a view in vertical cross-section on the line 3 3, Fig. 2. Fig. 35 4 is a plan view of the mechanism for supporting the platform, showing parts in horizontal section, the platform being removed. Fig. 5 is a view similar to Fig. 2, but showing 40 the doors in open position and the platform in its depressed position. Fig. 6 is a detail view showing a flexible connection of the operating-lever with the door.

I carry out my invention as follows: In the 45 drawings, *a* represents a floor, *b b* folding doors arranged to swing vertically upon their hinges, and *c* represents a yielding platform located in an opening or well in the floor and normally projecting slightly above the floor, 50 the floor being cut away a little longer than

the platform to permit a desired degree of endwise movement of the platform. Underneath the platform is a framework casing or other suitable support, (indicated at *d*.) secured in place in any suitable manner. Upon 55 said support or framework are located a series of bearings *e*, in which bearings are journaled, respectively, rock-shafts *f f*, preferably three in number, although I do not limit myself to any precise number thereof, three being preferably 60 used to evenly support the platform toward its extremities and intermediate thereof. The rock-shafts are provided with arms *g*. The rock-shafts and arms constitute together rocking arms, the arms *g* having a jointed connection, as shown, with corresponding brackets *h*, secured to the platform. The arms *g* are preferably so arranged as to swing either way from the longitudinal center of the rock-shafts *f* to carry the platform into depressed and elevated position, so 65 that the platform will have substantially the same movement either way from the horizontal center of said shafts. Such a construction will limit the movement of the platform to its lowest degree. It will be evident 70 that when a person steps upon a platform the rocking arms or shafts will be depressed with the platform, the arms *g* swinging in the arc of a circle, and consequently the platform 75 having an endwise movement upon the arc of a circle correspondingly, to permit which the well or orifice in the floor is made a little longer than the platform. The extremities 80 of the platform are preferably beveled or rounded to prevent the operator from stubbing thereagainst and by having the platform in depressed position descend substantially to the same level as the floor there will be no liability of stubbing against the floor 85 when leaving the platform.

The rock-shafts are preferably formed intermediate their ends with rigid upwardly-projecting arms *i*, with which are engaged one or more links or bars *j*.

I prefer to employ two bars connecting the individual rock-shafts, so that they will operate simultaneously. With the said bars are engaged retracting-springs *kk*, which may be secured at their opposite ends in any suit- 90 95 100

able manner to the supporting structures, the springs preferably extending in a horizontal plane with the bars *j*, as thereby the well in which the operating mechanism is located may be made of the least possible depth.

With one of the rock-shafts *f*—preferably with the middle rock-shaft—is engaged an upwardly-projecting operating-lever *l* for 10 each of the doors, the levers *l* being connected with the door by any suitable mechanism to actuate the door—as, for example, a connecting-rod *m*, jointedly connected with the respective door and with the adjacent lever. I 15 have shown in the drawings two doors *b b* and two operating-levers *l l*, suitably connected therewith; but I would have it understood that I do not limit myself to plural doors and plural levers *l*, as the mechanism would obviously 20 actuate a single door or may be made to actuate plural doors, as may be required.

In Fig. 6 I have shown a flexible connection *n*, suitably connected at its extremities with the door and with the corresponding 25 operating-lever *l*.

The operation of the device is obvious. When a party steps upon the platform, the platform is depressed, the rocking arms being rocked into downward position, operating 30 the levers *l* and opening the corresponding doors. When a person steps off from the platform, the pressure being relieved therefrom, the retracting-springs *k* restore the 35 rocking arms to normal position, and the door is consequently closed, the platform rising into its normal position. The platform being supported as above described is equally depressed at all points by weight of the person thereupon. The platform is constructed with elongated orifices, (indicated at 40 *p p*), through which the corresponding levers *l l* project to engage and operate the door.

Where a connecting-rod *m* is employed to connect the door with the lever *l*, said rod 45 will have a jointed engagement with the door and with the lever; but where a flexible connection is employed it need not have a jointed engagement at its extremities at adjacent parts, inasmuch as the flexibility thereof will 50 serve the same purpose as a jointed connection. The lever *l* may be made in two parts having an adjustable engagement the one with the other, if preferred, as by means of 55 bolts *q*, extending through an elongated slot in one portion of the said lever.

The position assumed by the mechanism connecting the platform with the door is such as to normally hold the door in closed position until the platform is depressed, the 60 springs *k* aiding in holding the door in closed position while the platform is in normal position. It will be seen that the devices connecting the upper ends of the levers *l* with the door are connected with the face of the corresponding door. I would have it understood 65

that I do not limit myself solely to the particular lever mechanism shown to connect the rocking arms with the door, as my invention contemplates the employment of any suitable mechanism for this purpose, whereby 70 the desired movements can be secured. The holding of the door in closed position, as above stated, to prevent the accidental opening of the door is a matter of importance. Extending the rocking arms or shafts transversely 75 underneath the platform and connecting the same at opposite ends with the platform affords firmness to the construction.

What I claim as my invention is—

1. A door-operating device comprising an inclosing support or casing fixed to the floor beneath an opening therein and having bearings, rock-shafts journaled in the bearings and having crank-arms rigid thereon, a yielding platform pivoted to the crank-arms, additional arms fixed on said shafts, a link connecting said additional arms, means connected to said rock-shafts to hold the platform elevated, and jointed mechanism connecting one of the rock-shafts with the door to open the latter when the platform is depressed.

2. In a door-operating device, the combination of a stationary support or casing 95 mounted beneath an opening in the floor, transversely-extending rock-shafts mounted upon said support, a yielding platform normally extending above the floor having direct pivotal connection with and supported by said rock-shafts, means connecting the rock-shafts, means to hold the platform in normally elevated position, and jointed mechanism connecting the rock-shafts and the door to open the door by the depression of 100 the platform, the platform when in depressed position descending to substantially the level of the floor.

3. In a door-operating device, the combination of a support or casing located beneath an opening in the floor, transversely-extending rock-shafts mounted upon said support, a yielding platform normally extending above the floor and having direct pivotal connection with and supported by said rock-shafts above the opening in the floor, means 110 connecting the rock-shafts, a spring to hold the platform in normally elevated position, and mechanism connecting the rock-shafts and the door to open the latter by the depression of 115 the platform, the platform when in depressed position descending to substantially the level of the floor.

4. A door-operating device comprising a support or casing located beneath an opening in the floor, bearings carried by said support, transversely-extending rock-shafts journaled in the bearings provided with crank-arms rigid thereupon, a yielding platform 125 pivotally connected to the crank-arms and 130

normally extending above the floor, means to hold the platform in normally elevated position, and mechanism connecting one of the rock-shafts with the door to open the latter when the platform is depressed, the platform when in depressed position descending to substantially the level of the floor.

- 5 5. The combination with a door, of means for opening and closing said door comprising transversely-extending rock-shafts having crank-arms, a yielding platform normally extending above the floor pivoted to and supported by the said crank-arms, means 10 above the rock-shafts connecting the rock-shafts, a retracting-spring above the rock-shafts to restore the platform to normal position, a lever-arm on one of the rock-shafts, and a jointed connection between said lever- 15 20 arm and the door for opening and closing the door, said door when in depressed position descending to substantially the level of the floor.

6. A door-operating device comprising a support located in an opening in the floor, rock-shafts mounted thereupon, a platform having a jointed connection with the rock-shafts, means connecting the rock-shafts with the door to open the door when the platform 25 is depressed, a link connecting the rock-shafts and located thereabove, and a spring connected with one of the rock-shafts thereabove to restore the platform to normal position.

30 7. A door-opening device comprising a support located in an opening in the floor, transversely-extending rock-shafts mounted thereupon, a yielding platform having a jointed connection with the rock-shafts, means connecting one of the rock-shafts 35 40

with the door to open the door when the platform is depressed, said rock-shafts provided with upwardly-extending arms, links connecting said arms, a spring secured at one end thereof to said links and at the opposite end of said support in a plane above the rock-shafts.

8. In a door-operating device, the combination of a support or casing fixed to the floor beneath an opening therein transversely-extending rock-shafts mounted thereupon, a yielding platform pivotally connected to and supported by said rock-shafts above the opening in the floor, a link above the rock-shafts connecting the rock-shafts, a 55 spring above the rock-shafts to hold the platform in normally elevated position, and mechanism connecting the rock-shafts and the door to open the door by the depression of the platform, said rock-shafts provided with crank-arms to support the platform and with additional upwardly-projecting arms with which said link is connected.

9. In a door-operating device, the combination with a door, of rock-shafts having 65 rigid crank-arms, a yielding platform pivoted directly to the crank-arms, a link above the rock-shafts connecting the rock-shafts, an arm on one of said shafts, an oscillatory lever, a rod connecting the door and the lever, and a retracting-spring to automatically close the door.

In testimony whereof I have signed this specification in the presence of two subscribing witnesses.

LOUIS IVES.
